PERFORATED CARD INTERPRETER

Irving B. Knutson, Chicago, Ill., assignor to International Business Machines Corporation, New York, N. Y., a corporation of New York

Application August 26, 1938, Serial No. 226,859

4 Claims. (Cl. 101—93)

This invention relates to printing mechanisms and more particularly as applied to types of machines known as interpreters in which character representing perforations on record cards are analyzed and the characters represented thereby are printed back on the controlling record cards.

A machine of this type, known as the "International alphabetic interpreter", is shown and described in Patent No. 2,076,713 granted to E. A. Ford April 13, 1937, and the present invention relates specifically to the improvement of the type carrier interrupting mechanism of such machine to the end that the machine may be operated at greater speed and with less wear.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

In the drawings:

Fig. 1 is a central section through the card feeding, sensing and printing mechanism.

Fig. 1a is an isometric of the friction drive device for the type carrier.

Fig. 2 is a detail position view of the type carrier and its operating mechanism.

Fig. 3 is a wiring diagram of the electric circuits of the machine.

Fig. 4 is a further position view of the type carrier and its operating mechanism.

Fig. 5 is a timing chart of certain of the machine controlling devices.

In the following, the general operation of the machine will be but briefly described with the improved type carrier arrangement explained in greater detail. For a more detailed explanation of the machine, reference may be had to Patent No. 2,076,713 and to facilitate cross-referencing the reference characters used in this application correspond to those designating the same parts in the patent.

Perforated record cards placed in a feed hopper A are advanced singly from the bottom of the stack by a picker knife 23 which is mounted for horizontal reciprocation by lever 21. The knife 23 feeds each card through gauge or throat blocks 24 to feed rollers 25 which advance the card to the sensing brushes 32 and in transit thereto the card engages the usual card lever 29 to close a pair of control contacts.

As the card continues its advance, it will pass between the brushes 32 and contact drum 33. A set of feed rollers 34 carried on rods 35 cooperate with the drum 33 to effect further advance of the record card. The drum is provided with gripping fingers (not shown) arranged to hold the card against the surface of the drum while the card passes through printing position.

As set forth in the patent referred to, drum 33 advances with an intermittent motion and with varying speeds which may be briefly explained in connection with the timing diagram of Fig. 5. The record card has twelve index point positions designated R, X, O, 1, 2, 3, 4, 5, 6, 7, 8 and 9 and they pass the sensing brushes 32 in this order. The first three positions known as "zone" positions advance slowly, past the brushes, with an interval between the sensing of each as indicated along the line designated D in Fig. 5. The drum then rests for a brief interval and then advances the remaining positions at a more rapid, uniform rate. By this time circuits completed through the perforations have positioned the type carriers as will be explained and the drum 33 then again rests to hold the card in printing position to receive an imprint from the type elements. Thereafter, the drum resumes operation to advance the card to rollers 67 which convey it to the discharge hopper B. Brake arm 17 on shaft 78 assists in bringing drum 33 to rest and prevent over throw due to inertia.

The machine is provided with a plurality of type bars 96 each having four groups of type elements 94, the individual type of which are horizontally slidable for printing purposes. Extending across the type bars along the printing line is the impression structure 153, which supports plungers 152 and is bodily slidable to the right by cam 151 and returned by leaf spring 159 and bell crank 160.

Each type bar or carrier 96 is provided with an undercut slot 96a to receive the upper end of a link 99 (see Fig. 1a). The upper end of the link is split as shown and the spring tension therein causes it to press firmly against the sides of the slot. The lower extremity of the link is T shaped and fits within a retaining groove in crosshead 128 (Fig. 1). The crosshead is guided vertically in a slot 129 in member 130 and reciprocation is effected through a lever 131, which has pin and slot connection with the crosshead 128 and is controlled from cam 135 on shaft 114 through member 132 on rod 133. Cam 135 serves to move the crosshead downwardly and a second complementary cam on shaft 114 and a suitable follower

(not shown) on rod 133 returns the crosshead to its upper position.

It follows from the construction described that as the crosshead 128 reciprocates, the type bars 5 move down and again up therewith, the friction link 99 serving to keep the relationship between the two as shown in Fig. 1. In the patent the carrier is normally held against movement with the crosshead and if a carrier is not to be used, 10 there is a sliding of the link within slot 99a which produces a load on the driving mechanism and wear of the frictionally engaged parts. In the present construction, the carrier is normally free to move up and down with the cross- 15 head and in those positions (of which there are sixty provided) in which no printing is to be effected the heretofore extra drag on the crosshead is eliminated.

Each carrier 96 has a plurality of teeth 100 cut 20 in one edge which as the carrier descends successively pass the nose of a normally retracted stopping pawl 101. Energization of magnet 103 as the carrier descends will attract its armature 104 to release a spring pressed bell crank 105 25 which will thereupon push call rod 107 to the right and advance pawl 101 into engagement with a tooth 100 to stop the carrier 96 against further movement with the crosshead, the friction connection allowing relative displacement between 30 the carrier and crosshead.

The timing of the machine is such that as the index point positions R, X and O are at the sensing brushes 32, the teeth 100 designated R, X and O will be adjacent to the stopping pawl 101, and if 35 there is a perforation in one of such positions the carrier will be interrupted by engagement of pawl 101 with the related tooth 100. Assuming a perforation in the O position of a card column, the circuit is traceable in Fig. 3 from generator G, 40 card lever contacts 31, wiper 183, common ring of distributor D, O segment 184, brush 185, common contact 81, drum 33, brush 32, to socket 172, plug connection 173 to socket 174 and magnet 103 back to generator G.

45 At the time of the completion of this circuit, the O tooth 100 is opposite pawl 101 and will be engaged thereby to hold the carrier in substantially the position it occupies in Fig. 2. In this position the group of type elements designated 50 Zone "O" are in readiness to pass the printing position opposite drum 33.

After the R, X and O positions have been sensed and before the positions 1 to 9 are at the brushes 32, pawl 101 is positively retracted to free the 55 carrier for resumption of travel with crosshead 128. The retracting mechanism comprises a cam 300 mounted on shaft 114 which acts on a follower 301 and through arm and link connection 302 rocks a ball 303 to move pawl 101 to the 60 left. Subsequently, the carrier 96 moves downwardly with the type elements 94 in the "O" zone group passing the printing position as the digit positions 1-9 in the card pass the sensing brushes and upon sensing of a hole in one of 65 such positions magnet 103 is energized a second time to again interrupt the movement of the carrier with one of the type elements in the selected zone group in printing position.

70 Similarly, if the first energization of magnet 103 were in response to the sensing of a hole in the R position, the carrier would be interrupted with the elements of the lowermost or R zone group in readiness to pass the printing position and after pawl 101 is withdrawn, a second energization of magnet 103 would select a type ele-

ment in this group according to the digital value of the second hole sensed.

Where a card column contains only a single perforation in a digital position 1-9, the carrier is not initially interrupted and the type elements 5 94 in the uppermost group pass the printing position as the corresponding index point positions are sensed and a circuit completed in response to a hole will stop the carrier in position to print the appropriate digit. 10

For selection of alphabetic characters there is therefore a direct advance of the carrier to position the appropriate zone group of type elements in readiness to pass printing position and when all zones are adjusted there is a resumption of 15 movement of the carriers and a second selection to present one of the elements in the first selected zone group to the printing position.

As in the patent, provision is made to effect an accurate alignment of the carriers prior to the sensing of the digit positions 1-9. This is brought about by rocking balls 142 from the position of Fig. 1 to that of Fig. 2. These balls are pivoted to the reciprocating slide 130 which is operated through a lever 138 pivoted at 138 and engaged by a cam 140 on shaft 114. Each ball has a pin 144 extending into a slot 145 in a lever 146 pivoted at 147. The lower extremity of lever 146 is connected by a rod 148 to lever 148 pivoted at 150 and engaged by a cam 151 on shaft 114. 30 The timing and operation of these parts is as set forth in the patent and is briefly as follows. Shortly after the zone holes R, X and O are sensed, balls 142 are rocked to the position of Fig. 2, this taking place while the balls are held in 35 their uppermost position and while crosshead 128 continues its descent. Then as the index point positions 1-9 pass the brushes, balls 142 move down in synchronism therewith, while the ball 128 continues therewith at the same rate. The 40 critical point lies in the fact that there is a slight delay between the release of the type carriers and the commencement of descent of balls 142 during 45 which ball 128 moves the carriers down against the upper edges of the balls so their subsequent movement is controlled thereby.

While there has been shown and described and pointed out the fundamental novel features of the invention as applied to a single modification, it will be understood that various omissions and 50 substitutions and changes in the form and details of the device illustrated and in its operation may be made by those skilled in the art without departing from the spirit of the invention. It is the intention therefore to be limited only as indicated by the scope of the following claims. 55

What is claimed is:

1. A printing mechanism having a reciprocable type carrier provided with a plurality of type elements, an invariably reciprocable crosshead, a frictional connection between the crosshead and carrier, means for moving said crosshead, said crosshead normally moving the carrier with it through said frictional connection, means for interrupting the carrier by engagement therewith during the movement of the crosshead in one direction, means for disabling said interrupting means by disengaging the same from the carrier at a fixed time during the movement of the crosshead in said direction and record controlled 70 means for causing an operation of said interrupting means before and after said fixed time to effect a cumulative displacement of the carrier with respect to the crosshead. 75

2. A printing mechanism having a reciprocable

type carrier provided with a plurality of type elements, an invariably reciprocable crosshead, a frictional connection between the crosshead and carrier, means for moving said crosshead normally, said crosshead moving the carrier with it through said frictional connection, means for interrupting the carrier by engagement therewith during the movement of the crosshead in one direction, means for disabling said interrupting means by disengaging the same from the carrier at a fixed time during the movement of the crosshead in said direction and record controlled means for causing an operation of said interrupting means at a differential time before and again at a differential time after said fixed time to effect a displacement of the carrier with respect to the crosshead a distance determined by the two differential times of interruption.

3. A printing mechanism having a reciprocable type carrier provided with a plurality of groups of type elements, an invariably reciprocable crosshead, a frictional connection between the crosshead and carrier, means for moving the crosshead and the carrier with it through said

frictional connection, to cause the groups of type elements, element by element, to pass a printing position in succession, record controlled means operative prior to the passage of any group of type elements to interrupt the movement of the carrier and hold the same in interrupted position, means operative at a later fixed point in the movement of the crosshead for disengaging said interrupting means and thereby enabling resumption of the movement of the carrier with the crosshead, said record controlled means being operative again to interrupt the movement of the carrier during the passage of the elements of the next following group to stop one of said elements in printing position.

4. The invention set forth in claim 3 in which the type carrier is provided with teeth, the interrupting means comprises a pawl engageable with said teeth to stop and hold the carrier and the means operative at a fixed time comprises a cam controlled member for withdrawing the pawl from engagement with the teeth.

IRVING B. KNUTSON.
